UNITED STATES PATENT OFFICE.

WILLIAM J. ROBINSON, OF ROCHESTER, NEW YORK, ASSIGNOR TO
BARNARD & SIMONDS COMPANY, OF NEW YORK.

DESIGN FOR A CHAIR-FRAME.

SPECIFICATION forming part of Design No. 34,511, dated May 14, 1901.

Application filed February 23, 1901. Serial No. 48,630. Term of patent 7 years.

To all whom it may concern:

Be it known that I, WILLIAM J. ROBINSON, a citizen of the United States, and a resident of Rochester, in the county of Monroe and State of New York, have invented and produced a certain new and original Design for a Chair-Frame, of which the following is a specification.

The drawing shows a perspective view of a chair-frame embodying the said design.

The body portion of the chair-frame is rectangular and is composed of the similar flat side pieces $a a$ and the similar flat front and rear pieces $a' a'$. The upper and the lower edges of the side pieces $a a$, respectively, are parallel and formed in the same ogee curve. The front and rear pieces $a' a'$ are rectangular. All of the pieces $a a$ and $a' a'$ are set in vertical planes. At two adjacent corners of the rectangular frame are vertical square pieces $b b$, extending above and below said frame. At the other two corners of said frame are pieces $b' b'$, substantially square also and extending vertically to the top of

said frame and then outward and inward in 25 gentle ogee curves, as shown. Other pieces c , that are broad horizontally and narrow vertically, pass from the pieces $b' b'$ to the tops of the pieces $b b$ in gentle ogee curves that are substantially parallel to the curves at the 30 edges of the side pieces $a a$. From the top of that one of the pieces a' of the rectangular body portion that connects the pieces b' and between the pieces b' there pass a series of parallel strips d , that are substantially rectangular in cross-section and extend upward in curves that are parallel to those of the curved portions of the pieces b' . Passing from the upper end of one piece b' to the upper end of the other piece b' there is a piece 40 e , in which the strips d terminate.

What I claim is—

The design for a chair-frame as herein shown and described.

WILLIAM J. ROBINSON.
